UNITED STATES PATENT OFFICE.

GEORGE S. KECK, OF SPRINGFIELD, OHIO.

PROCESS OF PRODUCING COLORED LIME.

1,195,140.

Specification of Letters Patent. Patented Aug. 15, 1916.

No Drawing.

Application filed August 28, 1913. Serial No. 787,219.

To all whom it may concern:

Be it known that I, GEORGE S. KECK, a citizen of the United States, residing at Springfield, in the county of Clark and 5 State of Ohio, have invented certain new and useful Improvements in Processes of Producing Colored Lime, of which the following is a specification.

This invention relates to a powered lime 10 having coloring matter incorporated therein and the process of producing such lime.

As is well known lime is extensively used as the principal ingredient of decorative coatings applied to walls and the like, one 15 form of which is the "white coat" commonly applied to plastered walls. It is often desirable that this decorative coating should be tinted or colored and attempts have been made to color the lime when it is mixed with 20 the other ingredients preparatory to applying it to the walls. This process, however, of placing the coloring in the mixture when it is prepared for application to the walls has not been wholly successful, as almost 25 invariably the color will be unevenly mixed and the wall will be streaked. This is particularly true where a smooth finish is applied to the wall. If the wall has a roughened surface the unevenness and streakiness 30 of the color is not so apparent but it is still present.

In order to overcome this difficulty and provide a uniformly tinted coating for the walls or other surfaces it is the object of 35 the invention to produce a lime having the coloring matter incorporated therein during the process of its manufacture, thereby insuring a uniform distribution of the color in the lime and enabling the tint desired to 40 be selected before the mixture is made.

In carrying out my invention I have applied the same to what is known as hydrated lime. As is well known lime comes from the kiln in lumps and in order to place 45 the same upon the market in a powered condition it must be treated in some manner. A very common treatment is what is known as hydration, which consists in grinding the lumps into a coarse granulated form, mixing 50 the same with water, drying this mixture and then screening the same. The detail steps of the process are not essential to an understanding of the present invention nor is it necessary to illustrate the apparatus 55 employed. Suffice it to say that the mixing and drying apparatus, commonly known as

a hydrator, may be of various kinds. One well known hydrator comprises a series of cylinders having mixing devices within the same. The granulated lime is placed in the 60 upper cylinder and a predetermined quantity of water added thereto and thoroughly mixed therewith. The process of mixing also tends to feed the mixture from the first cylinder to the second cylinder and so on 65 through the series of cylinders. The drying is effected by the heat generated by the mixture of the lime with the water, which heat is sufficient to thoroughly dry the lime before it leaves the hydrator. It is not to 70 be understood, of course, that the lime is chemically dry but that it is commercially dry.

In order that the coloring matter may be properly incorporated in the lime I prefer to add the same thereto during some 75 step of the process of pulverization, which, in the present instance, is the process of hydration. More or less satisfactory results may be obtained by applying the coloring matter at different times during this 80 process but one very satisfactory method consists in adding the coloring matter to the quantity of water which is to be mixed with the lime during the process of hydration and before the water is added to the lime. In this manner the coloring matter 85 is carried to every particle of the lime and is thoroughly and uniformly incorporated therewith and when dry and screened the 90 product is perfectly smooth and of an absolutely uniform coloring and the most delicate tints of any shade or color may be secured. However, if the coloring matter is mixed with the lime and water in the hydrator, the hydrating operation will cause 95 it to be very thoroughly incorporated with the lime and a smooth uniform product will be had. A wide variation of colors may be secured, this being accomplished, of course, 100 by varying the character and amount of coloring matter employed. Various coloring matters can be used and the amount of coloring matter employed to secure a specified tint will depend largely upon the character 105 of the coloring matter itself and may be determined in the first instance by experiment. After a little experience the person preparing the mixture can determine by the color of the water before it is applied to 110 the lime the color of the finished product, but in practice I find that a specified quan-

5 tity of a given coloring matter, say, five pounds to forty gallons of water, will always produce the same tint in a given quantity of the finished product. While the
10 5 amount of coloring matter added to the water to color a given amount of lime will vary with the different coloring matters used the following may be given as an example: If fifty pounds of raw sienna is
15 10 mixed with fifty gallons of water and the resulting mixture is used in the hydration of about fifteen hundred pounds of lime there will be obtained a hydrated lime of a pale yellow tint. By increasing or decreasing
20 15 the percentage of dry color the color of the hydrated lime will be proportionately darker or lighter. The product when finished is substantially of the same character as the hydrated lime of commerce, and the
25 20 product is handled and applied in essentially the same manner as the hydrated lime.

It will be understood that while I have described the process of producing this product this process may be varied to a greater or less extent without departing
30 25 from the essential principles thereof. For example, the coloring may, as above stated, be applied to the lime at different steps in the course of its preparation for the market.

30 Having thus fully described my inven-

tion, what I claim as new and desire to secure by Letters Patent, is:—

1. The process of producing uniformly colored hydrated lime consisting in uniformly disseminating coloring matter 35 throughout a body of water, adding only enough of such water to unhydrated lime to hydrate the lime and leave it in the form of a dry powder, and thoroughly mixing the lime and water during hydration. 40

2. The process of producing uniformly colored hydrated lime, consisting in placing together in a hydrator the lime to be hydrated, and only enough water to hydrate the lime and leave it in the form of dry powder and enough coloring matter to produce the desired color, and thoroughly mixing the same to cause the water to combine with the lime, to uniformly incorporate the coloring matter with the lime and to cause 45 the colored lime to be dried in the form of a powder by the heat generated in the hydrator by the mixture of the lime and water. 50

In testimony whereof, I affix my signature in presence of two witnesses.

GEORGE S. KECK.
